UNITED STATES PATENT OFFICE.

JOHN E. HOY, OF MIDLAND, MICHIGAN, ASSIGNOR TO THE DOW CHEMICAL COMPANY, OF MIDLAND, MICHIGAN, A CORPORATION OF MICHIGAN.

WORKING LIGHT METALS.

Application filed November 15, 1926. Serial No. 148,440.

This invention relates to the working of light metals, and more particularly where structural elements of harder metal are also present; and it is among the objects of the 5 invention to provide a method securing an adequate treatment of the light metal and at the same time an effective union between the respective elements. Other objects and 10 advantages will appear as the description 10 proceeds.

To the accomplishment of the foregoing and related ends, the invention, then, consists of the features hereinafter fully described, and particularly pointed out in the 15 claims, the following description and the annexed drawing setting forth in detail but one of the various ways in which the principle of the invention may be employed.

In said annexed drawing: 20 Fig. 1 is a central vertical sectional view illustrating one way of carrying out the invention; and Fig. 2 is a perspective view showing the resultant form of the article illustrated as undergoing the procedure.

The light metals, as magnesium, aluminum, and their alloys, while having many dominant advantageous qualities, are of less 25 strength than iron, and while immaterial in many uses, in some instances it is desirable to include the properties of both metals. If the light metal be subjected to semi-plastic flowage and compression, the inherent strength can be materially increased and the surface texture, density and finish 30 greatly improved; and in the present invention, I subject the metal to compressive flowage at the same time in relation with a structural element of heavy metal.

In the illustrative form shown, a piston 40 casting 1, mounted on a dis-assemblable core 2 of any suitable construction is started into a die 3 and is forced through, for instance by the blows of a power hammer on the cap 4. The piston blank 1 is provided 45 with an annular shoulder 5 and an annular shoulder 6, and above the latter the head is of corresponding larger diameter, and rings 7 and 8 of iron or steel are carried by the blank abutting the respective shoulders.

With the rings 7 and 8 preliminarily as-

sembled with the blank 1, each ring seated against its respective shoulder 5 and 6 and the metal heated to a temperature enabling efficient working, e. g. 600-900° F. in the instance of magnesium, the assemblage is 55 forced along. The die or the blank, preferably the die, has a taper, and the light metal is forced to flow into the space between the rings 7 and 8 and be drawn into compact, smooth form, firmly embedding 60 the rings, and presenting a dense tough surface. In this manner, not only is the strength of the light metal itself increased by molecular rearrangement and adjustment, but the harder metal elements of the 65 assemblage are united in effective union, such that the surface presents a good working finish.

While the process is particularly well 70 adapted for the finishing of piston blanks, it is of course applicable to other articles where molecular flowage and a union with harder metal elements into a composite structure is to be accomplished, and while 75 iron or steel were instanced as the harder metal, it will be understood of course that other metals may be employed as desired.

Other modes of applying the principle of the invention may be employed, change being made as regards the details described, 80 provided the steps stated in any of the following claims or the equivalent of such be employed.

I therefore particularly point out and 85 distinctly claim as my invention:—

1. In a method of the character described, the steps which consist in assembling a light metal blank with an element of harder metal and die-drawing the assemblage to 90 flow the light metal and at the same time embed the harder element.

2. In a method of the character described, the steps which consist in assembling a light metal blank with spaced elements of hard metal and die-drawing the assemblage to 95 flow the light metal and at the same time embed the hard elements.

3. In a method of the character described, the steps which consist in assembling a cylindrical light metal blank with a surface 100

ring of hard metal and die-drawing the assemblage to flow the light metal along the surface and at the same time embed the hard ring.

5. 4. In a method of the character described, the steps which consist in assembling a cylindrical light metal blank with spaced

surface rings of hard metal and die-draw-
ing the assemblage to flow the light metal
along the surface and at the same time em- 10
bed the hard rings.

Signed by me this 2nd day of November,
1926.
